ABSTRACT

A method and apparatus for characterizing defect levels and assigning valuations to these levels to enable the rejection of tapes containing defects exceeding predetermined levels, the apparatus including a series of resistive dividers which are weighted in determining the depth of a defect and a series of monostable multivibrators for determining duration, each of these factors having progressive values assigned thereto, a matrix responsive to combinations of depth and duration for determining the annoyance value of a defect, and an output for accumulating the annoyance levels.

METHOD OF TESTING MAGNETIC RECORDING CARRIERS FOR DEFECTS IN THE MAGNETIC LAYER

The invention relates to a method of testing magnetic recording carriers, hereinafter to be referred to as tapes, for defects in the magnetic coating. A test signal of substantially constant amplitude is recorded on the tape and subsequently is scanned so as to produce a signal which consists of the original signal on which pulses due to defects in the tape have been superimposed, said pulses being counted in a counter when their duration exceeds a predetermined value.

The known devices as described above have the disadvantage that in determining the annoyance caused by the fault no allowance is made for the degree in which these faults are perceived by human beings, with the result that tapes are rejected unnecessarily, as practice has shown.

This disadvantage is avoided by applying, according to the invention, the scanned signal to a device which records both the depth and the duration of the pulses, and assesses these properties as a function of psychological and physiological factors.

The term "depth of a defect" is used in this specification to mean the ratio, expressed as a percentage, between the minimum voltage electrically representative of the said defect and the voltage of the test signal. The duration of a defect is determined by the time interval between those points on the leading and trailing edges of the wave shape envelope of the voltage of the defect at which the amplitude has dropped 3 dB. Perception research has proved that a defect of a duration less than 10 ms, whatever its depth, does not cause annoying disturbances in music signals. In the present method, the defect duration is divided into, for example, three classes, i.e. class 1: from 10 to 20 ms, class 2: from 20 to 50 ms, and class 3: longer than 50 ms. The perception research has resulted in a scale of 12 annoyance values, i.e. values which determine the annoyance caused by a defect and which are given in the following annoyance or h table.

TABLE

Depth of defect, percent	Greater than														
	66	63	57	53	49	44	40	36	32	27	23	19	15	10	5
Duration of defect (in ms.)	10-20	20-50	50-100	100-200	200-500	500-1000	1000-2000	2000-5000	5000-10000	10000-20000	20000-50000	50000-100000	100000-200000	200000-500000	500000-1000000
10-20	1	1	1	2	1	1	1	2	2	3	3	4	4	5	6
20-50	1	1	1	2	3	4	5	5	6	7	8	9	10	11	12
50-100	1	2	3	4	5	6	7	8	9	10	11	12	12	12	12

100000-200000	1	2	3	4	5	6	7	8	9	10	11	12	12	12	12
200000-500000	1	2	3	4	5	6	7	8	9	10	11	12	12	12	12
500000-1000000	1	2	3	4	5	6	7	8	9	10	11	12	12	12	12

In one embodiment of the method according to the invention, in order to determine the annoyance value of the scanned signal, the duration of the pulses produced by scanning is converted in the apparatus into a signal which is applied to a first input of a matrix associated with the respective scan, the relative depth of the defect is measured in stages and the resulting signal is applied to a second input of the said matrix associated with the respective stage after which the signal appearing at an output of the matrix associated with two inputs is applied to a circuit arrangement which converts the signal into a number of pulses, which number is associated with this output, after which the pulses are applied to the counter.

An annoyance value n of 1 indicates that although a small decrease in sound volume is heard, it is not experienced as annoying. Only a h of 2 is regarded as annoying. Hence, in another embodiment of the method only those defects which exceed a given value are allowed to pass by a threshold device. If a defect having a given annoyance value is followed by a second defect having a higher annoyance value, the annoyance caused by the second defect is found to be equal not to its full annoyance value but only to the difference between this value and the annoyance value of the greatest preceding defect. Hence, in a further embodiment of the method according to the invention, only that part of the value of each succeeding defect is recorded which exceeds the value of the greatest preceding defect.

It has also been found that the occurrence of more than one defect causes an additional annoyance which is to be assessed by an additional value, such as an additional point, irrespec-

tive of its absolute value. For this purpose, in a further embodiment of the method of the invention each defect succeeding the first one and having a value exceeding a given threshold value is additionally assigned a constant number of additional counting pulses.

If, for example, within 1 second more than one defect occurs, this proves to be experienced as increasingly annoying. Therefore, in a further embodiment of the method according to the invention the signal is supplied to a circuit arrangement which in the case of several pulses occurring in quick succession advances the counter a number of steps, which number is equal to the number of these defects.

An apparatus for carrying out the method comprises a magnetic head for scanning the signal recorded on the tape and an amplifier for amplifying it. Also a first rectifier including appropriate circuitry is provided having a time constant greater than the duration of the longest defect for producing a reference voltage, a second rectifier including appropriate circuitry is provided having a time constant smaller than the duration of the shortest annoying defect, and an attenuator the input of which is connected to the second rectifier and tappings of which are connected to first inputs of a plurality of threshold detectors to first inputs of which the voltage of the first rectifier is applied. The output of the first threshold detector is connected through a first output of a first pulse shaper to a time circuit comprising a first monostable multivibrator having a reset time of about 10 ms which through a first output is coupled to an input of a second monostable multivibrator having a reset time of about 20 ms a first output of which is connected to a third monostable multivibrator having a reset time of about 50 ms, which multivibrators simultaneously change states. A second output of the first monostable multivibrator and the first output of the second monostable multivibrator are connected to inputs of a first and-gate, a second output of the second monostable multivibrator and the

first output of the third monostable multivibrator are connected to a second and-gate. A second output of the first pulse shaper is connected to the reset inputs of the monostable multivibrators and also to the first inputs of third, fourth and fifth and-gates to second inputs of which the outputs of the first and second and-gates and the second output of the third monostable multivibrator are connected, the outputs of the third, fourth and fifth and-gates being connected to first inputs of a matrix the second inputs of which are connected to the other threshold detectors each through a defect-depth store. This store comprises a bistable multivibrator, as the case may be with the interposition of pulse shapers, the outputs of the matrix, which each are associated with a given annoyance value, being connected to a counter.

Features and advantages of the invention will appear from the following description of an embodiment thereof, given by way of example only, with reference to the accompanying drawings, in which:

FIG. 1 shows the variation of the annoyance value h as a function of the defect duration and the defect depth;

FIG. 2 shows the manner in which the curves of FIG. 1 may digitally be approximated;

FIG. 3 shows the manner in which the time duration and the depth of a defect are defined;

FIG. 4 is a block-schematic diagram of an apparatus for carrying out the method; and

FIG. 5 shows as functions of time the voltages which appear at the outputs of the various circuit elements of FIG. 4 when a defect occurs.

Referring to FIG. 1, there are shown the curves of 4 annoyance values as a function of defect duration t and defect depth G for the audio range. The graphs clearly show that a defect of less than 10 ms duration causes negligible annoyance whereas in the case of a time duration exceeding 10 ms the annoyance scarcely increases with time.

FIG. 2 shows how the curves of FIG. 1 may reasonably be approximated digitally by the choice of three time intervals, namely from 10 to 20 ms, from 20 to 50 ms, and longer than 50 ms. Obviously, the curves may be approximated more closely by increasing the number of time intervals.

FIG. 3 shows that the duration of a defect is determined by those points on the leading and trailing edges of the interference voltage at which the voltage of the continuous signal has decreased by 3 dB, i.e. at the value of about 70 percent of the peak value of the continuous signal. The depth of the defect is defined by the ratio between the smallest d and largest D amplitudes of the continuous signal expressed as a percentage.

In FIG. 4, the voltage from a magnetic head 1 is applied through an input attenuator 2 to an amplifier 3, through one output of which the amplified signal is applied to a rectifier G_1 , having a time constant larger than that of the longest defect, the output voltage of this rectifier serving as a reference voltage for the defect depth to be measured. The second output of the amplifier 3 is connected to a rectifier G_2 having a time constant of approximately 3 ms. The output of the second rectifier G_2 is connected to an attenuator V the tappings on which are connected to first inputs of a number of threshold detectors DD_{70} to DD_5 which each are associated with a given level, the subscripts indicating the depth of a defect as a percentage. The output of the first rectifier G_1 is connected to second inputs of the threshold detectors DD_{70} to DD_5 . The outputs of those threshold detectors which each deliver a pulse when the defect reaches the depth indicated by the respective subscript are each connected to a respective pulse shaper PS_{70} to PS_5 . A first output of the pulse shaper PS_{70} is connected to an input of a first monostable multivibrator OS_{10} having a reset time of about 10 ms, a first output of the multivibrator being connected to an input of a second monostable multivibrator OS_{20} which has a reset time of about 20 ms and a first input of which is connected to a third monostable multivibrator OS_{50} having a reset time of about 50 ms, these three multivibrators being simultaneously caused to change states by a pulse from the pulse shaper PS_{70} . A second output of the first monostable multivibrator OS_{10} and the first output of the second monostable multivibrator OS_{20} are connected each to one input of an and-gate N_1 , a second output of the second monostable multivibrator OS_{20} and the first output of the third monostable multivibrator OS_{50} are connected each to one input of a second and-gate N_2 , a second output of the pulse shaper PS_{70} being connected to the reset inputs of the monostable multivibrators OS_{10} , OS_{20} and OS_{50} and also to first inputs of third, fourth and fifth and-gates N_3 , N_4 and N_5 , the second inputs of which are connected to the outputs of the first and second and-gates N_1 and N_2 and to the second output of the third monostable multivibrator OS_{50} , respectively, whilst the outputs of the third, fourth and fifth and-gates N_3 , N_4 and N_5 are connected to first inputs a , b and c of a matrix M , the second inputs 2 to 12 of which are connected to the threshold detectors DD_{63} to DD_5 each through a pulse shaper PS_{63} to PS_5 and to a fault-depth store comprising bistable multivibrators FF_{63} to FF_5 , respectively, second inputs of which multivibrators are connected to the first output of the pulse shaper PS_{70} which at the beginning of a fault resets the fault-depth store.

In FIG. 5, 1a indicates the variation of a direct voltage during a defect having a depth between 70 percent and 53 percent. When a depth of 70 percent is attained, the threshold detector DD_{70} delivers a pulse the duration of which is equal to the duration of the defect and which is shown by b . This pulse is given steeper edges (c) in the pulse shaper PS_{70} and then is applied to the defect-depth store comprising the bistable mul-

tivibrators FF_{63} to FF_5 , which are reset to their initial states and is also applied to the first monostable multivibrator OS_{10} , which changes state and in turn causes the second monostable multivibrator OS_{20} to change state, which in turn causes the third monostable multivibrator OS_{50} to change state. The voltages at the outputs of these multivibrators are indicated by j , k and l , respectively. Shortly afterwards the threshold detectors DD_{63} to DD_{53} are rendered operative so as to deliver pulses to the pulse shapers PS_{63} to PS_{53} , respectively, which in turn cause the bistable multivibrators FF_{63} to FF_{53} , respectively, which serve as the defect-depth store and have been reset by the pulse shaper PS_{70} on the 70 percent limit being reached, to change state. The output voltages of these bistable multivibrators are indicated by g , h and i , respectively. When the end of the defect is reached, the threshold detector DD_{70} and also the pulse shaper PS_{70} change state again and because the and-gate N_2 associated with the time interval from 20 to 50 ms is open a pulse, indicated by n in FIG. 5 can be transmitted to the input b of the matrix M . With this combination there is associated an annoyance value of 2, so that at an output h_2 of the matrix a pulse of the shape indicated by n in FIG. 5 appears, which causes a change of state of a bistable multivibrator FF_2 of an annoyance register H comprising bistable multivibrators FF_2 to FF_{12} , the subscripts indicating the associated annoyance values, so that the multivibrator FF_2 transmits a pulse to a counter T , through an or-gate O , and causes a change of state of a monostable multivibrator $OS_{20}\ \mu$ which returns to the initial state after 20 μ s and transmits a second pulse to the counter T through the or-gate O . These pulses are indicated in FIG. 5 by o to q .

The internal connections of the matrix are designed such that only annoyance values greater than 1 will be transmitted to the annoyance register H .

Unlike the fault-depth store, which is reset for each defect, the annoyance register H is not reset. Consequently, during a measurement the register is progressively filled.

If the second defect in the tape should also have an annoyance value 2, the annoyance register H does not respond to it, because the bistable multivibrator FF_2 has already changed state.

If the third defect should have an annoyance value 4, the multivibrators FF_3 and FF_4 change states with the result that after 30 and 40 μ s monostable multivibrators $OS_{30\mu}$ and $OS_{40\mu}$, respectively coupled to the said bistable multivibrators each deliver a pulse through the or-gate O to the counter so that a 4 is set in it. Thus for each subsequent defect only that part of the annoyance value is registered which exceeds the value of the largest preceding defect.

Since the results of the perception research show that each defect following the first and having a value greater than a given threshold value causes additional annoyance, each defect following the first and causing an annoyance greater than 3 must additionally be assigned an additional counting pulse in that after each defect the bistable multivibrator FF_4 is automatically reset by the resetting of the pulse shaper PS_{70} . If the first defect is followed by a fault having an annoyance value at least equal to 4, the bistable multivibrator FF_4 again changes state and thus transmits an additional pulse to the counter through the associated monostable multivibrator $OS_{40\mu}$ and the or-gate O .

When defects occur in rapid succession, the annoyance caused proves to be extra serious and hence they are assigned an additional number of counting pulses by the circuit arrangement in the following manner.

At the first defect having an annoyance value at least equal to 2 a pulse is applied to a monostable multivibrator OS_1 having a reset time of 1 s, so that an and-gate N_6 the two inputs of which are coupled to a first output and to the input of the monostable multivibrator OS_1 is opened. If within 1 s a second defect having an annoyance value at least equal to 2 occurs, the gate allows the pulse at the output h_2 of the matrix M to pass, so that a bistable multivibrator A connected to the output of the and-gate N_6 changes state and through the or-gate O

delivers a pulse to the counter and in addition causes a monostable multivibrator D to change state, which after 10 μ s transmits a second pulse to the counter. If three defects occur within 1 s, the bistable multivibrator B also changes state. If four or more defects occur, a bistable multivibrator C also changes state and applied a pulse to the counter through the or-gate O. After 1 s the and-gate N₆ is closed because of the fact that the monostable multivibrator OS₁ is reset and in addition the ruffle counter comprising the bistable multivibrators A, B and C is reset.

More than four defects per second cause no increased annoyance, so that any further defects within this period are not recorded.

What is claimed is:

1. A device for testing record carriers defects in the record layer on which layer a constant amplitude test signal has been recorded comprising a magnetic head for scanning said signal recorded on said record layer and an amplifier electrically coupled to said head for amplifying said signal, a first rectifier means electrically coupled to said amplifier and having a time constant greater than the duration of the longest defect and serving to produce a reference voltage in response to an input voltage from said amplifier, a second rectifier means electrically coupled to said amplifier for producing an output voltage in response to an input voltage from said amplifier and having a time constant smaller than the duration of the shortest annoying defect, an attenuator having a plurality of tappings thereon, the input of said attenuator being connected to the second rectifier, said tappings connected to respective first inputs of a plurality of multi-input threshold detectors, means coupling said reference voltage of the first rectifier means to respective second inputs of said threshold detectors, the output of the first of said threshold detectors being connected to the input of a first pulse shaper, a first output of said first pulse shaper being connected to a time circuit comprising a first monostable multivibrator having a reset time of about 10 ms, which through a first output is connected to an input of a second monostable multivibrator having a reset time of about 20 ms, a first output of which is connected to a third monostable multivibrator having a reset time of about 50 ms, which multivibrators are mutually interconnected so as to simultaneously be caused to change states, a second output of the first monostable multivibrator and the first output of the second monostable multivibrator are each connected to an input of a first and-gate, and a second output of a second monostable multivibrator and the first output of the third monostable mul-

tivibrator are connected to a second and-gate, a second output of the first pulse shaper connected to the reset inputs of all of said monostable multivibrators and also to first inputs of third, fourth and fifth and-gates each having at least two inputs, the 5 second inputs of said and-gates having connected thereto the outputs of the first and second and-gates and the second output of the third monostable multivibrator, respectively, the outputs of the third, fourth and fifth and-gates connected to first inputs of a matrix, second inputs of which are connected 10 to the outputs of the remaining threshold detectors each through means for storing a magnitude corresponding to defect-depth, the outputs of the matrix each associated with an assigned designation representing a given annoyance value being connected to a counter.

15 2. The combination of claim 1 wherein an output of said matrix is coupled to a further circuit including a monostable multivibrator having a predetermined time delay, a plurality of pulse producing means coupled to said monostable multivibrator, and an output coupling said pulse producing means

20 to said counter for counting additional annoyance values in response to a matrix output representing a rapid succession of defects.

3. A method of testing record carriers for defects in the record layer to determine the perceptual annoyance caused by

25 said defects comprising placing a predetermined assignment of weighted annoyance values to predetermined combinations of depths and durations of defect signals, recording a test signal of constant amplitude on said carrier, separately measuring the depth and duration of each defect signal, wherein

30 the depth of a defect is defined as the ratio of the voltage of said defect signal to the voltage of said test signal, combining and correlating the measured depth and duration of each defect signal to determine its annoyance value in accordance with said predetermined assignment, recording the annoyance

35 value of each defect if it is above a predetermined minimum, and accumulating the annoyance values of all defects on said carrier under test.

4. A method as claimed in claim 3, wherein for each succeeding defect only that part of said annoyance value is 40 recorded which exceeds the annoyance values of the greatest preceding defect.

5. A method as claimed in claim 3, wherein each defect following the first and having a level greater than a given threshold level, is assigned a constant additional annoyance value.
